UNITED STATES PATENT OFFICE.

CYRUS BERRY PEETS, OF NEW HAVEN, ASSIGNOR TO ROGERS & BROTHIER,
OF WATERBURY, CONNECTICUT.

DESIGN FOR A SPOON, &c.

SPECIFICATION forming part of Design No. 21,385, dated March 8, 1892.

Application filed February 1, 1892. Serial No. 419,996. Term of patent 14 years.

To all whom it may concern:

Be it known that I, CYRUS BERRY PEETS, of New Haven, in the county of New Haven and State of Connecticut, have invented a new 5 Design for the Handles of Spoons and Forks; and I do hereby declare the following, when taken in connection with accompanying drawing, to be a full, clear, and exact description of the same, and which said drawing constitutes 10 part of this specification, and represents a face view.

This invention relates to a design for the handles of spoons, forks, and like articles; and it consists in the shape and ornamentation as hereinafter described, and shown in 15 the accompanying illustration. The handle in outline, starting from near the body, gradually expands to its broadest point at the ball

of the handle, thence gradually contracting by a convex curve, producing the appearance 20 of a long point or lancet shape. Around the edges of the handle, starting from a point about midway of the handle and upward to the point, is the representation of a rococo border, leaving a plain panel within the border, 25 as shown in the accompanying illustration.

I claim—

The design for the handles of spoons and forks, as herein shown and described.

In testimony whereof I have signed this 30 specification in the presence of two subscribing witnesses.

CYRUS BERRY PEETS.
